CIRCUIT INTERRUPTER

Raymond H. Leitzel, Forest Hills, and William H. Ware, Wilkinsburg, Pa., assignors to Westinghouse Electric & Manufacturing Company, East Pittsburgh, Pa., a corporation of Pennsylvania

Application May 26, 1942, Serial No. 444,498

14 Claims. (Cl. 200—48)

This invention relates in general to electric circuit interrupters, and more particularly to disconnecting switches of the type having a reciprocating blade.

Heretofore switches having a reciprocating contact have been proposed with the reciprocating contact movable either parallel or at right angles to the supporting porcelain insulators. Both of these types of switches require considerable space, and fail to take into consideration the mechanical weakness of porcelain insulators, especially with respect to shock and bending stresses.

One object of this invention is to provide a novel arrangement of a disconnecting switch of the reciprocating blade type and a contact supporting insulator, to reduce the space requirements of such switches and distribute the stress on the porcelain.

Another object of this invention is to provide for a disconnecting switch, novel shock-absorbing, and self-aligning contact mounting means.

Another object of this invention is to provide a disconnecting switch of the reciprocating blade type with novel contact means cooperable therewith.

These and other objects of this invention will become more apparent upon consideration of the following description of a preferred embodiment thereof when taken in connection with the attached drawing, in which:

Figure 1 is a side view of a disconnecting switch embodying this invention;

Fig. 2 is an enlarged side view of the switch contact and support therefor;

Fig. 3 is an end view looking from the right-hand side of Fig. 2, and

Fig. 4 is a section through the contact taken substantially on the line IV—IV of Fig. 2.

The particular switch illustrated in Fig. 1 of the drawing is especially adapted for use in conjunction with an air circuit breaker such as that disclosed in the copending application of L. R. Ludwig et al. Serial No. 431,394, filed February 18, 1942, and assigned to the same assignee of this application.

In general, the switch contact is adapted to be mounted on an insulating structure such as the insulator 2 shown in Fig. 1, which may be of any desired insulating material preferably porcelain or the like. The insulator 2 may be hollow if desired, for the reception of other electrical apparatus, and is provided with a cover structure 4 having an offset hood 6 secured thereto for housing the switch contact structure 8. The switch blade 10 is longitudinally slidably

mounted in a cylinder 12, for actuation by a fluid under pressure such as compressed air. As shown in Fig. 1, a hood 14 may be provided for the blade actuating cylinder if desired, and the cylinder and hood supported on any desired insulating support such, for example, as the circuit breaker supporting insulators shown in the aforesaid copending application.

An important feature of this invention resides in the switch contact construction, which, as shown in Fig. 2, comprises a base 16 adapted to be rigidly secured in the insulator cover structure 4, for example, as by being bolted thereto, and this base is provided with a slightly raised, substantially centrally located thrust bearing surface 18. A yoke member 20 has the intermediate portion thereof seated on bearing surface 18, and is pivotally mounted in bearing relation therewith by a pivot bolt 21. The free ends of yoke 20 carry a pivot pin 22 for pivotally supporting about an axis transverse with respect to the axis of pivot bolt 21, a contact support 24. The contact support 24 includes a base plate 26 angularly bent intermediate its ends, and a reinforcing rib 28 integral therewith. One end of the contact support provides a flat terminal pad 30 for securing a line conductor thereto, and this end is also provided with a substantially centrally located, downwardly depending flange 32. The flange 32 is provided at its lower end with an elongated slot 34 adapted to receive a stop pin 36 mounted in spaced ears 38 provided integral with supporting base 16. Coil compression springs 37 are provided on pin 36 at opposite sides of flange 32. This structure will obviously have the effect of limiting pivotal movement of the contact support about pivot pin 22 an amount determined by the extent of slot 34, and springs 37 will normally maintain contact support 24 at the position shown and will resiliently oppose rotation about pivot 21 in either direction. A coil compression spring 40 is seated in a depression in base 16, and bears against the contact support in a manner to bias it in a counterclockwise direction about pivot 22, to normally maintain the contact support in the position shown in Fig. 2.

The other end of the contact support has a contact assembly 42 secured at the outer end thereof, and a relatively large mass 44, which may be formed integral with the contact support, and located on the side of the contact assembly adjacent pivot 22, but spaced from this pivot.

Contact assembly 42 is mounted in a substantially rectangular-shaped enclosure 46 secured to

the outer end of plate 26 of the contact support, for example, as by the machine bolts 48. A pair of contact fingers 50 are disposed at opposite sides of, and within, contact enclosure 46, and are each pivotally mounted on a pivot pin 54 near the adjacent side walls of the enclosure. As shown, the contact fingers may be provided with divergent outer ends, with an inset 52 of an arcing material such, for example, as a tungsten alloy or the like. Contact fingers 50 are biased towards each other by a coil compression spring 58 for each contact, engaging between the adjacent wall of contact enclosure 46, and the base of an annular slot 56 formed in the contact fingers for preventing lateral escape of the springs. Each contact finger is provided centrally of annular slot 56, with an outwardly projecting stud 60 fixed thereto, and passing centrally through coil compression springs 58 and through a slot 62 opening to the free edge of the contact enclosure. Outwardly of the contact enclosure, studs 60 are provided with stop members maintained in position by nuts 64 threaded thereon, to limit movement of the contact fingers toward each other under the influence of springs 58. Contact fingers 50 are electrically connected to plate 26 of the contact support by means of a flexible shunt 66, of any suitable flexible conducting material, such, for example, as braided or laminated copper ribbon, or the like. Shunt 66 has the ends thereof connected to the respective contact fingers, for example, as by rivets 68, and the intermediate portion of the shunt is maintained in engagement with the plate portion 26 of the contact support by a bolt 70. The particular contact assembly 42 described above is designed with especial regard to ease of assembly, and it can be seen that the contact fingers may be first assembled to flexible shunt 66 and then with springs 58 in place they may be inserted into enclosure 46 with studs 60 entering slots 62. The pivots 54 may then be assembled, and shunt 66 secured to plate 26 by bolt 70, and the assembly will be complete.

In the operation of the switch constructed in accordance with this invention, assuming that the switch is in closed circuit position as shown in Fig. 1 of the drawing, it will be apparent that the circuit may be opened by withdrawal of blade 10 to a position spaced from contact structure 8, whereupon the contact structure will assume the position shown in Figs. 2 and 3 of the drawing. Now, when it is desired to close the circuit, the blade 10 is moved by the operating fluid into engagement with the contact structure 8 with a considerable force. Because the relatively large mass 44 increases the inertia of movable contact support 24, and because movement of contact support 24 in a clockwise direction about pivot 22 is further opposed by spring 40, the impact of the blade on the contact will be substantially absorbed by these two means. Disconnecting switches of this type which are used for high voltages require greater spacing between the switch blade support and insulator 2 as the voltage increases. With such greater spacings, there may be some bending or vibration of blade 10, especially when it is moved at a relatively high speed, so that the tip of the blade may not be perfectly aligned between contact fingers 50. Moreover, the tolerances possible in manufacturing porcelain insulators are relatively high so thereby further increase the chance that the contact fingers will be out of line with the switch blade. However, this is taken care of in accordance with this invention by the pivotal

mounting of contact support 24 on pivot bolt 21, so that upon closing the switch, if the tip of the switch blade 10 is not exactly aligned with the space between the contact fingers, it will act on the inclined edge of these fingers to rotate contact support 24 about pivot 21 against the bias of one of springs 37. Obviously, when the switch is open, springs 37 will return contact support 24 to a position wherein flange 32 thereon is intermediate ears 38 on base 16.

The impact and consequent strain on insulator 2 is further reduced by providing the switch blade 10 to move in a path extending at an acute angle of approximately 45° with respect to the longitudinal axis of the insulator. By this arrangement, the force on the insulator due to impact of the switch blade is divided into vertical and horizontal components, thereby decreasing both of these components, while, at the same time, decreasing the space dimensions required by the switch in its operation. It is believed readily apparent that if the switch blade operates in a horizontal path, greater horizontal space would be required than with the arrangement shown in Fig. 1, and similarly, if the switch operates in a vertical path, greater vertical space would be required than is required by the switch shown in this figure. The most important result of this switch arrangement probably is the reduction of the component of force exerted upon impact of the blade tending to bend insulator 2, because insulators of this type are relatively weak with respect to forces exerted in a manner tending to bend the porcelain.

Having described a preferred embodiment of the invention in accordance with the patent statutes, it is desired that the invention be not limited to the particular embodiment disclosed, inasmuch as it will be obvious, particularly to persons skilled in the art, that many modifications and changes may be made in this particular embodiment without departing from the broad spirit and scope of this invention, as defined in the appended claims.

45 We claim as our invention:

1. In a disconnecting switch, contact means, blade means mounted for movement into and out of engagement with said contact means, means pivotally mounting said contact means at a point spaced laterally of the contacting portion of said contact means to permit limited bodily movement of said contact means with said blade means in the plane of blade movement, and means pivotally mounting said contact means for limited pivotal movement in a plane extending angularly with respect to the plane of blade movement.

2. In a disconnecting switch, contact means, blade means mounted for movement into and out of engagement with said contact means, means mounting said contact means for limited movement in the plane of blade movement and in an angularly related plane, and resilient means biasing said contact means toward said blade means and normally maintaining said contact means at an intermediate point in its path of movement in said angularly related plane.

3. In a disconnecting switch, contact means, blade means mounted for movement into and out of engagement with said contact means, means mounting said contact means for limited movement in the plane of blade movement and in an angularly related plane, resilient means biasing said contact means toward said blade means, and additional spring means normally maintaining

said contact means at an intermediate point in its path of movement in said angularly related plane.

4. In a disconnecting switch, contact means, blade means mounted for movement into and out of engagement with said contact means, means mounting said contact means for limited movement in the plane of blade movement, a relatively large inertia mass associated with said contact means in a manner to resist movement of said contact means, resilient means biasing said contact means towards said blade means, the mounting of said contact means and the location of said mass relative thereto being such that said mass does not cause any initial stress on said resilient means.

5. In a disconnecting switch, contact means, blade means mounted for movement into and out of engagement with said contact means, means mounting said contact means for limited movement in the plane of blade movement and in an angularly related plane, resilient means biasing said contact means toward said blade means and normally maintaining said contact means at an intermediate point in its path of movement in said angularly related plane, and a relatively large inertia mass associated with said contact means.

6. In a contact construction, a contact supporting member mounted for limited pivotal movement about angularly related axes, and contact means mounted on said member at a point such that said contact means faces along a line which is offset from at least one of said axes.

7. In a contact construction, a contact supporting member mounted for limited pivotal movement, contact jaws opening in one direction of said pivot movement and mounted on said member at a point spaced from said pivot, a relatively large inertia mass on said member at a point spaced from said pivot, and resilient means biasing said member for pivotal movement in said one direction.

8. In a disconnecting switch, contact means, blade means mounted for movement into and out of engagement with said contact means, means mounting said contact means for limited movement laterally of the plane of movement of said blade means, and resilient means normally maintaining said contact means at an intermediate point of its path of movement.

9. In a contact construction, a contact supporting member mounted for limited pivotal movement, contact jaws opening in one direction of said pivot movement and mounted on said member at a point spaced from said pivot, resilient means biasing said member for pivotal movement in said one direction, said member also mounted for limited pivotal movement about a second axis at an angle to said first mentioned axis, and resilient means normally maintaining said member at an intermediate point in its path of movement about said second axis.

10. In a contact construction, contact supporting means having spaced, opposed supporting members connected at least at one end thereof, opposed contact fingers supported between said members for movement towards and away from each other, resilient means urging said fingers towards each other, and unitary flexible shunt means having the ends thereof connected to the inner ends of said fingers, respectively, and an intermediate portion thereof connected with said end connection between said supporting members so that said shunt means is confined within said supporting means.

11. In a contact construction, contact supporting means having spaced, opposed supporting members, opposed contact fingers supported between said members for movement towards and away from each other, coil compression springs between said fingers and said members, respectively, and annular recesses in said fingers for receiving the major portions of said springs to prevent lateral escape of said springs.

12. In a contact construction, contact supporting means having spaced, opposed supporting members, opposed contact fingers supported between said members for movement towards and away from each other, coil compression springs between said fingers and said members, respectively, annular recesses in said fingers for receiving adjacent end coils of said springs to prevent lateral escape of said springs, studs secured to each finger and extending through each spring and said members, said studs provided with outer stop portions for limiting movement of said contact fingers towards each other under the influence of said springs.

13. In a contact construction, contact supporting means having spaced, opposed supporting members, opposed contact fingers supported between said members for movement towards and away from each other, coil compression springs between said fingers and said members, respectively, annular recesses in said fingers for receiving adjacent end coils of said spring to prevent lateral escape of said springs, studs secured to each finger and extending through each spring and through slots opening to the free ends of said members, said studs provided with outer stop portions for limiting movement of said contact fingers towards each other under the influence of said springs.

14. In a disconnecting switch, contact means, blade means mounted for movement into and out of engagement with said contact means, means mounting said contact means for limited movement in the plane of blade movement, resilient means biasing said contact means towards said blade means, and a relatively large inertia mass associated with said contact means in a manner such that the weight of said mass also biases said contact means toward said blade means.
